ABSTRACT: In a walking-needle sewing machine or the like having a cyclically moving work point or tool, means for automatically feeding a curvilinear edge of a workpiece beneath the tool including means adapted to establish the position of the curvilinear edge with respect to the work point, and a drag-steering means activated thereby. The drag-steering means comprises in a preferred embodiment a spring-loaded contact face that reciprocates synchronously with the needle, normally lightly contacting the surface of the workpiece at a point laterally spaced from the work point. When activated, the drag-steering means exerts a firm restraining force on the workpiece so that the workpiece is retarded by and traces a shortened path under the point of contact of the drag-steering means as the workpiece is advanced through the machine by the walking needle and advancement mechanism, and the edge thereof rotates towards the work point. The material is guided or caused to rotate in the opposite direction as may be required by means of a guide or fence on the side of the needle opposite from the drag-steering means.

DRAG-STEERING WALKING-NEEDLE MACHINE

Prior Art

U.S. Pat. No. 2,971,483 (Cordier) discloses a sewing machine with a conventional feed dog mechanism with means for feeding a workpiece along a predetermined line or trace, in particular the contour of the workpiece. The patentee provides means on either side of the work point for impaling the workpiece while the needle is raised which when activated causes the workpiece to pivot about the impaling points. The means for impaling the workpiece do not, apparently, reciprocate synchronously with the needle, and since the workpiece is impaled, the turning moment is sudden and sharp as no provision is made for the workpiece to, while impaled, slip past the pivot point during the time the pivoting action is being exerted.

THIS INVENTION

This invention is an improved arrangement for automatically feeding or guiding the curvilinear edge of a workpiece such as cloth goods past or under the work point of a sewing or like machine having a cyclically moving work point.

The improvement of this invention is particularly applicable to a walking-needle machine used for hemming, binding, overcasting and the like sewing operations on materials having relatively stiff and/or heavy body characteristics, for example, canvas, denim, fabric with body, leather, or other like materials.

In addition to the components usual to a conventional sewing machine, e.g., a work surface, a reciprocating sewing needle, means for advancing the workpiece, etc., the apparatus of the invention comprises:

1. control means adapted to establish the work path of the workpiece with respect to the needle work point or work path; and
2. means, here referred to as a drag-steerer, for causing, as required on command from the control means, the workpiece to trace a curvilinear path through a point laterally spaced from the work point, so as to cause a point in the work path on the workpiece in advance of the work point to turn about and into the work point.

While this invention is particularly directed to stitching at or near the curvilinear edge of a workpiece, it will be appreciated that it need not be so limited; as the control means, e.g., a photoelectric sensor, could as well follow a predetermined curvilinear path to effect stitching anywhere in the interior of the workpiece or the work path to be followed could be programmed as with a counter or a computer, for example. Also, a second drag-steerer can be used on the opposite side from that shown so that the workpiece can be made to turn into the work path from the opposite direction.

THE DRAWINGS

In the drawings:

FIG. 1 illustrates a walking-needle machine incorporating the improvements of this invention operating to attach a binding tape to the edge of a shoe quarter;

FIG. 2 is an enlarged perspective view of the stitching operation of FIG. 1, viewed from the point of the feed of the workpiece into the machine;

FIG. 3 is a perspective view of the working area from the discharge side and shows in greater detail the action of the drag-steerer when it is not exerting its guiding action;

FIG. 4 is the same as FIG. 3 except that it shows the drag-steerer at a time when it is exerting its guiding action;

FIG. 5 is a schematic illustration of one type of edge scanning means and command circuit that can be used in the practice of this invention;

FIG. 6 illustrates a type of drag-steerer that can be used, in particular the mechanism for activating the drag-steerer so that it exerts a predetermined firm restraining or steering force on the workpiece when desired, and

FIG. 7 diagrammatically illustrates the action of the apparatus of this invention.

Like parts have the same number throughout the drawings.

DESCRIPTION

With reference to the drawings, the number 10 represents generally a walking-needle machine operating to attach a binding tape 16 to the edge of a workpiece such as a shoe quarter 15. The sewing machine has a conventional stitching needle and guide generally indicated at 11 which reciprocates along the line of the work as better illustrated in FIG. 3, and helps to advance the workpiece past the work point. The workpiece 15 is suitably introduced to the workpoint, and the binding tape 16 is fed from a supply roll 17 illustrated in FIG. 2 (but not illustrated in FIG. 1).

As is known, the stitching needle of a walking-needle sewing machine reciprocates vertically engaging and disengaging the workpiece. The needle also cyclically walks along the work path while engaging the workpiece and disengages itself from the workpiece and returns to the point of beginning. In accordance with the invention a drag-inducing means is made to reciprocate with the needle, and when called upon to do so, exerts a drag-steering force upon the workpiece. As illustrated, the drag-force or pressure-inducing member is in the form of a foot or shoe 36 mounted in a housing 30.

The housing 30 is coupled to a guide shaft 31 which rides in a support 32. The support 32 is attached to the machine 10. The guide shaft 32 is caused to reciprocate synchronously with the needle by means of a cam 33 acting on the top of the shaft 31, the shaft 31 being biased away from the bed of the machine 10. The cam 33 is driven by the same power source as the machine 10 by driving the cam 33 via shaft 34.

In addition, in the embodiment illustrated, a sensing means is used to determine the position of the edge of the workpiece 15 with respect to a sensing point slightly in advance of the stitching needle work path. As illustrated, this is a photoelectric cell arrangement, schematically illustrated in FIG. 5 and shown in the other Figures as consisting of a light source 40 shining through an opening 42 in the bed or working surface onto a photoelectric cell 43. A reflecting means or mirror could as well be placed on the work surface so that cell 43 could be located thereabove.

The cell 43 (FIG. 5) provides an electric output proportional to the amount of light received. When the light intensity is reduced, as by the workpiece covering all or a large part of the opening 42, the output of the cell 43 is reduced and such output applied to the amplifier-threshold 44 is blocked by such threshold. When the light intensity is increased as by a large part or all of the opening 42 being uncovered, the output of the cell 43 is increased and such output applied to the amplifier. Threshold 44 is passed to energized solenoid 50 so that solenoid 50 extends its plunger 51, and thus the hammer 52 is driven or pressed against the activating lever or locking lever bar 39. The threshold function of the threshold amplifier 44 is preferably adjusted so that the threshold level corresponds to the electric output of the photocell 43 at one half normal maximum light intensity of the source 40.

With reference to FIG. 6, one type of drag-steering mechanism that employs a force or pressure exerting device to exert a controlled predetermined force or pressure on the surface of a workpiece can consist of a shoe or foot 36 coupled to a shaft. The shaft and shoe 36 are carried in a housing 30 which is connected to a guide shaft 31. Such device may be similar to the device described and claimed by Donald M. Husted in a copending application entitled "Controlled Force Applicator" filed on the same day as the present application and assigned to a common assignee. The housing 30 is caused to move synchronously with the needle so that the shoe or foot 36 makes contact with the workpiece 15 during part or all of the time the needle 12 is engaged with the workpiece 15, during the sewing cycle.

Without actuation of the locking level bar 39 as by energization of the solenoid 50 extending the plunger 51 and contact-

ing hammer 52, the collar 38 is free to travel with respect to the housing 30. When the shoe 36 contacts the surface of the workpiece 15 and the housing 30 continues to approach the surface, the shoe 36 and its shaft recede into the housing and compress weak spring 35, spring 37 being substantially stronger than spring 35. Thus the shoe 36 is made to contact the surface of workpiece 15 with a relatively light, resilient force or pressure permitting the workpiece to slide 74 with little effort under the shoe as the workpiece is advanced with the aid of the walking mechanism of the sewing machine.

It will be appreciated that the workpiece need be of a relatively heavy-bodied material as opposed to a flimsy fabric or other material.

When the locking lever bar 39 is actuated, the bar 39 communicates with the collar 38 and limits the travel of the collar 38 with respect to the housing 30. When the shoe 36 contacts the surface of the workpiece 15 and the housing 30 continues to approach the surface of the workpiece, the shoe 36 and its shaft recede into the housing, but the collar 38 is prohibited from receding into the housing; and as the shoe and shaft move, the strong spring 37, located between the collar 38 and the shoe 36, becomes compressed; and the shoe 36 is forced with a strong, resilient force or pressure against the surface of the workpiece 15 providing a large resistance to the advancement of that part of the workpiece in contact with the shoe so that the workpiece is dragged through the contact point 71 in a shortened path 72. Since the travel of the workpiece through the contact point 71 is reduced in length and the travel of the workpiece engaged by the needle 73 at 75 FIG. 7 remains the same, the workpiece is made to pivot about the needle as the needle moves along the work path 75 thereby dragging with it the edge or path p toward alignment p' with the work path. The point p on the path or edge of the workpiece 15 is shown on a curve portion of the workpiece path or edge receding from the reciprocal of the extension of the work path 75.

As the needle 12 becomes disengaged from the workpiece 15, the shaft 31 follows the ascension of the needle, and the force exerted by the shoe 36 is released.

Shoe 36 need not act upon the workpiece the whole of the cycle time the needle is engaging the workpiece. As described below, the shoe 36 can be controlled to apply a restraining force only during a portion of this time, particularly if only a limited control action is required.

If the workpiece 15 is not extending over opening 42, as shown in FIG. 4, the drag-steerer is activated to exert the just described firm restraining force. If the workpiece 15 does extend over the sensing point 42, as illustrated in FIG. 3, the drag-steerer is not activated to exert its firm restraining force but instead exerts only its normal light contact force.

The sewing machine may also include a guide or flange 19 to cause the tape 16 to curl about the edge of the workpiece. This guide 19 can also be used to guide the edge of the workpiece underneath the needle if the workpiece because of its curvilinear shape tends to extend over or beyond sensing point 42 as illustrated in FIG. 2. However, when only using one drag-steering system as in the embodiment shown, it is preferred to also place a fence 18 on the side opposite from the side the drag-steerer operates on, to aid in the guiding of the material past the work point.

When the machine commences its stitching action and the workpiece 15 starts to move forward in cooperation with the walking needle, the edge of the workpiece 15 may extend beyond sensing point 42 or fall short thereof. If it falls short of covering substantially half of the sensing opening 42, the light intensity passing through the opening 42 will activate the photoelectric cell and will thereby cause the drag-steerer, as it reciprocates, to contact the work surface with a firm restraining or dragging force, with some slippage thereunder, which 70 force will cause the fabric to trace a shortened path under the contact point and to pivot about the moving (walking) needle and thrust the edge (p) back into line (p') with sensing point 42. If the edge of the material as it moves forward tends to extend over sensing point 42, then guide 19 will provide passive 75

opposition and will effectively nudge the edge of the material to a position where it is over sensing point 42 and to line up with the work path of the needle.

With reference to FIG. 7, it can be seen clearly that this invention contemplates that the workpiece is never totally restrained from movement by the restraining force exerted by the drag-steerer, shown as a contact point 71. Instead when the drag-steerer exerts its controlling pressure, some slippage is permitted such that the workpiece traces a shortened path 72 away from the initial work point of the needle 73. This shortened path under the contact point is made somewhat shorter in length equivalent to the linear distance 74, depending upon the length of time the dragging pressure is maintained during engagement of the needle in the workpiece during each stitching cycle. The locking lever bar 39 may be so biased that should the workpiece edge be steered away from and expose the opening 42 during a stitching cycle, the output of the photocell 43 may fall below the threshold level, and the solenoid may become deenergized and release its plunger 51 and hammer 52 permitting the locking lever bar 39 to release collar 38 and thereby relieve the pressure applied on shoe 36 by spring 37. This will effectively release the drag-steering force applied to the workpiece 15 prior to normal release, during the cycle of operation.

When the control force is released, a point p on the curvilinear path 77 (which may be the edge of the workpiece 15 or a path across the surface of the workpiece) to be followed by the workpiece is thrown towards and into the work path 75 of the needle, i.e., the point p moves curvilinearly towards p' about the axis of the needle as the needle moves along the work path 75.

It is noted that a conventional walking-needle machine includes a presser foot as shown in FIG. 2, associated with the needle guide 11. This presser foot is omitted from FIGS. 3 and 4 for purposes of clarity of illustration of the invention.

It will be apparent that the shoe 36 has relatively low friction characteristics with respect to the material of the workpiece 15. While the mechanical drag-steering arrangement shown is preferred since it will not tend to soil the article being worked on, one skilled in the art will appreciate that a hydraulic activated arrangement can be used. A hydraulic piston can be used to exert the force created by spring 37 in the embodiment illustrated as the drag-steerer descends with the amount of pressure pulsed to the piston being controlled to regulate the amount of predetermined force that is applied against the surface of the workpiece.

Instead of an optical or photoelectric method for sensing the edge of the workpiece, a fluidic system or mechanical feeler, such as illustrated in the above-referred-to patent, could also be used to control activation of the drag-steering mechanism.

What I claim is:

1. In a sewing machine having a reciprocating walking needle that penetrates and stitches a relatively stiff form-stable workpiece in a work path and advancement means for advancing said piece along said work path; the improvement for automatically positioning said workpiece to permit the stitching to follow a curvilinear path, comprising:

control means adapted to establish said work path, and a drag steering means:

spaced laterally from said work path,
adapted to intermittently contact said workpiece at a point of contact in phase with the action of said needle,
said contact normally being a loose contact that permits said workpiece to slide thereunder, and
operatively connected to said control means and adapted to, upon command therefrom, exert a restraining action on said workpiece during at least a portion of the time said drag-steering means is in contact therewith, causing said workpiece in cooperation with said advancement means to follow a curvilinear path under said point of contact and a point on said edge in advance of said work path to turn into said work path.

2. The sewing machine of claim 1 wherein said control means comprises a sensor photoelectric cell and light source adapted to pass a sensing light beam through a sensing point generally orthogonally to said workpiece a predetermined distance of said work path, and further adapted when said edge does not extend over said sensing point to issue said command.

3. The sewing machine of claim 1 wherein said drag-steering means comprises a contact shoe, first and second springs adapted to act on said shoe, a housing guiding said shoe and said springs, and a spring checking means for checking one of said springs, said shoe normally being lightly restrained by the other of said springs when brought into contact with said workpiece as said drag-steering means reciprocates and brings said shoe into contact with said workpiece, and upon said command, said spring checking means serving to restrain said one of said springs with respect to said housing as said drag-steering means brings said shoe into contact with said workpiece, thereby compressing said one of said springs against said shoe and causing said shoe to exert said restraining action.

4. In a walking-needle sewing or like machine having means for advancing a planar workpiece through a work path on said machine's work surface, a workpiece guidance system for guiding said workpiece to said work path along a predetermined curvilinear path on said workpiece, an improved workpiece guidance system comprising, in combination:

control means adapted to determine whether said predetermined curvilinear path is to one side or the other of said work path, and further adapted to issue a command when said predetermined curvilinear path is on said one side; and

steering means adapted to reciprocate toward and away from the surface of said workpiece for repeatedly contacting the same with normally a light unrestraining pressure for permitting linear advance of said workpiece with the walking needle of said walking-needle sewing machine, and upon issuance of command by said control means for exerting a firm restraining pressure on, without penetration of, the surface of said workpiece at a point spaced laterally from said work path on said one side for causing said workpiece at said spaced point and at the location of said needle to arcuately divert from said linear advance under dragging restraint in cooperation with said firm restraining pressure on said workpiece at said spaced point and said means for advancing said workpiece for throwing a point on said curvilinear path in advance of said work path into said work path.

5. The machine of claim 4 wherein said predetermined curvilinear path is one edge of said workpiece and comprising in addition thereto an edge guide adapted to act on said one edge when said one edge tends to extend beyond said work path on said other side, and to guide thereby said edge over said work point.

6. Apparatus for steering a fabric workpiece or the like along a predetermined path through a work point of a machine having a tool which aids in cyclically advancing the workpiece through said work point, said steering apparatus

operating cooperatively with said tool, said machine including;

a work surface for supporting said workpiece, a predetermined track in said predetermined path defining said work point,

a tool adapted to perform work on said workpiece cyclically in which said tool engages said workpiece and travels along said predetermined track in a first direction and means adapted to advance said workpiece in said first direction cooperatively with said tool when said tool travels in said first direction along said predetermined track, and said steering apparatus including,

workpiece restraining means offset from said track, operating during at least part of the time that the tool engages said workpiece for reducing advancement in said first direction of a portion of said workpiece offset from said work point for causing said workpiece so engaged by said tool to pivot about said tool as said tool and said workpiece advance along said predetermined track in said first direction.

7. Apparatus for steering a fabric workpiece as in claim 6 and steering apparatus further includes

control means for controlling said workpiece restraining means for effecting dragging contact with said workpiece by said workpiece restraining means for altering the path of said workpiece presented to said tool.

8. Apparatus for steering a fabric workpiece as in claim 6 and said steering apparatus further includes

control means responsive to deviation of said workpiece from said predetermined path for effecting restraining contact by said restraining means with said workpiece for altering the path of said workpiece for conforming with said predetermined path.

9. Apparatus for steering a fabric workpiece as in claim 6 and in which said tool is a needle of a walking-needle sewing machine in which the needle engages said workpiece and travels along said predetermined track in said first direction while engaging said workpiece and disengages from said workpiece and returns to the point of beginning while disengaged from said workpiece and said workpiece restraining means includes

a reciprocating foot adapted to contact said workpiece and retard advancement of said workpiece at the point of contact, while permitting full advancement of said workpiece at said work point.

10. Apparatus for steering a fabric workpiece as in claim 9 and further including

control means for controlling said reciprocating foot for effecting advance-retarding contact by said foot with said workpiece during the time said needle is engaged with said workpiece.

11. Apparatus for steering a fabric workpiece as in claim 9 and further including

control means for controlling said reciprocating foot for effecting advance-retarding contact by said foot with said workpiece during a portion of the time said needle is engaged with said workpiece.
